US00D762117S

(12) **United States Design Patent**
Joseph et al.

(10) **Patent No.:** US D762,117 S
(45) **Date of Patent:** ** Jul. 26, 2016

(54) **BOTTLE LID**

(71) Applicant: Ignite USA, LLC, Chicago, IL (US)

(72) Inventors: David Joseph, St. Charles, IL (US);
Paul Hurley, Libertyville, IL (US)

(**) Term: 14 Years

(21) Appl. No.: 29/516,716

(22) Filed: Feb. 5, 2015

(51) LOC (10) Cl. 09-01

CLAIM

The ornamental design for a "bottle lid," as shown and described.

DESCRIPTION

FIG. 1 is a perspective view of a bottle lid showing a new design;
FIG. 2 is a left view thereof;

FIG. 3 is a right view thereof;

FIG. 4 is a back view thereof;

FIG. 5 is a front view thereof;

FIG. 6 is a top view thereof; and,

FIG. 7 is a bottom view thereof.

The broken lines are shown for the purpose of illustrating environmental subject matter and parts of the bottle lid that form no part of the claimed design.

1 Claim, 7 Drawing Sheets
